US0D1089410S

(12) United States Design Patent (10) Patent No.: US D1,089,410 S
(45) Date of Patent:  Aug. 19, 2025

(54) LABEL

- (71) Applicant: OSSTEM IMPLANT CO., LTD.,
Seoul (KR)
- (72) Inventors: Ha Eun Jang, Seoul (KR); Jae Kyeom Kim, Seoul (KR); Soo Yeon Shim, Seoul (KR); Yong Jin Kim, Seoul (KR)
- (73) Assignee: OSSTEM IMPLANT CO., LTD.,
Seoul (KR)
- () Term: 15 Years
- (21) Appl. No.: 35/521,943
- (22) Filed: Jul. 1, 2024

(80) Hague Agreement Data

- Int. Filing Date: Jul. 1, 2024
Int. Reg. No.: DM/238960
Int. Reg. Date: Jul. 1, 2024
Int. Reg. Pub. Date: Aug. 16, 2024

(30) Foreign Application Priority Data

- Jan. 10, 2024 (KR) 30-2024-0001268
- (51) LOC (15) Cl. 19-08
- (52) U.S. Cl.
USPC D20/24; D20/27
- (58) Field of Classification Search
USPC D20/10, 11, 12, 15, 29, 34, 22-28, 40,
D20/99; D14/485-495
CPC ... G09F 3/00; G09F 9/00; G09F 11/00; G09F
2003/021; G06F 3/04817; G06T 11/60
See application file for complete search history.

(57) CLAIM

The ornamental design for a label as shown and described.

DESCRIPTION

The file of this patent contains at least one drawing/photograph executed in color. Copies of this patent with color drawing(s)/photograph(s) will be provided by the Office upon request and payment of the necessary fee.

1. Label

1.0 is a front view showing our new design.

The broken lines in the reproduction depicts portions of the label that form no part of the claimed design.

1 Claim, 1 Drawing Sheet
(1 of 1 Drawing Sheet(s) Filed in Color)
